United States Patent Office

Des. 208,780
Patented Oct. 3, 1967

208,780

CHART POSITION INDICATOR

Charles A. Smith, 1177 NE. 158th St.,
North Miami Beach, Fla. 33162

Filed Sept. 9, 1966, Ser. No. 3,791

Term of patent 14 years

(Cl. D25—1)

FIG. 1

FIG. 2

FIG. 3

FIG. 4

FIGURE 1 is a side view of a chart position indicator showing my new design,

FIGURE 2 is a top plan view, and

FIGURE 3 is an end view from the left of FIG. 1; and
FIGURE 4 is an end view from the right of FIG. 1.

I claim:

The ornamental design for a chart position indicator, substantially as shown.
